By

UNITED STATES PATENT OFFICE.

LOUIS A. LEMKE, OF FULTON, ILLINOIS.

KITCHEN-RACK.

No. 919,896.

Specification of Letters Patent.

Patented April 27, 1909.

Application filed August 1, 1908. Serial No. 446,371.

To all whom it may concern:

Be it known that I, LOUIS A. LEMKE, a citizen of the United States, residing at Fulton, in the county of Whiteside and State of Illinois, have invented certain new and useful Improvements in Kitchen-Racks; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention has reference to kitchen racks, and is specially designed to be used for the support of kettle covers and other kitchen utensils, when not in use.

It is simple in construction and can be formed of one piece of material, whereby the cost of production can be greatly reduced.

In the drawings: Figure 1 is a perspective, showing my invention in position, when in use. Fig. 2 is a vertical section in the broken line $x-x$ of Fig. 1. Fig. 3 shows a blank from which the device may be formed, with the parts thereof indicated in broken lines.

Similar numbers refer to similar parts throughout the several figures.

The device is preferably formed of sheet metal, and consists of a plate 1, having an inwardly turned edge 2, and provided with triangular end plates 3, integral with which are flanges 4, provided with perforations 5 for screws or similar fastening means. The shape of the end-plates 3 is such as to incline the plate 1 outwardly and upwardly, forming a pocket for the reception of kettle covers, lids, and similar culinary articles. Extending downwardly from the plate 1 is a strip 6, provided with holes 7, by means of which the device can be still further secured in place. A narrow plate 8 is supported from the strip 6, by means of a flange 9, and a similar flange 10 is turned inwardly from the lower edge of the plate 8. If desired the flange 10 can be reinforced by a strip 11, turned backwardly there-

on. Supported on the plate 8 is a plurality of small hooks 12, preferably formed by being struck outwardly from such plate, as shown in the drawings, and upon such hooks may be suspended kitchen utensils of the smaller class, such as bread knives, spoons, and similar articles.

Fig. 3 illustrates the method of producing the device from one sheet of metal, the blank being first formed of suitable size and shape, and provided with the perforations 5 and 7. The various parts are then formed by bending at the proper points, along the lines indicated. It will be seen that there is a considerable space between the plate 8 and the rear line of the rack, by reason of which articles suspended upon the hooks 12 will be supported at some distance from the wall, and will not mar the same. The inwardly turned strip 2 at the upper edge of the plate 1 is for the purpose of strengthening such edge, and preventing the same from becoming bent by the articles supported thereby, but the use of such strip is not essential.

I do not wish to be understood as limiting myself to the exact form or use of the device as herein shown and described, as changes can be made in the construction thereof, and the same can be adapted for use in other places besides the one referred to herein, without departing from the spirit thereof.

What I claim as my invention, and desire to secure by Letters Patent of the United States, is:

In a device of the class named, a plate 1, provided with ends 3, means for holding said plate in place, and the plate 8, supported from the plate 1, and provided with a plurality of hooks 12, substantially as shown and set forth.

In testimony whereof, I affix my signature, in presence of two witnesses.

LOUIS A. LEMKE.
